UNITED STATES PATENT OFFICE.

HERMAN W. PAULUS, OF RICHMOND HILL, NEW YORK, ASSIGNOR TO ROYAL BAKING POWDER COMPANY, A CORPORATION OF NEW JERSEY.

METHOD OF CONVERTING FORMATES INTO OXALATES.

Original application filed July 26, 1920, Serial No. 399,085. Divided and this application filed September 19, 1921. Serial No. 501,735.

To all whom it may concern:

Be it known that I, HERMAN W. PAULUS, a citizen of the United States, and a resident of Richmond Hill, in the county of 5 Queens and State of New York, have invented certain new and useful Improvements in Methods of Converting Formates into Oxalates, of which the following is a specification.

10 The present invention relates to a method of converting formates into oxalates, and more particularly, to a method of converting alkaline formates into alkaline oxalates. This application is a division of my copending application Serial No. 399,085, filed July 15, 1920.

It has long been recognized that it is difficult economically to produce oxalates from formates on a commercial scale. The experiments seeking to increase the quantity of production and decrease the cost of production have covered a long series of years and involved the expenditure of much effort and capital. Heretofore these experiments have 25 been more or less unsuccessful with the result that the cost of oxalates is still relatively high. The object of the present invention is to produce a method of converting formates into oxalates by which the oxalates 30 may be produced quantitatively and at a relatively low cost. The conditions under which formates may be converted into oxalates are well recognized. When the formate is subjected to a temperature ranging 35 from 360° C. to 440° C., a molecule of hydrogen is driven off in accordance with the following formula (sodium formate is taken to illustrate the reaction):

40 Up to 220° C. the formate is stable. Subjected to a temperature ranging between 220° C. and 360° C., the formate is converted into a carbonate. If the formate is subjected to a temperature exceeding 440° C., the formate will pass through the oxalate state and be converted into carbonate exclusively.

45 With these conditions governing the production of oxalates from formates, it has been proposed to carry on the conversion in closed vessels. This has been found dangerous unless an inert gas is used for

displacing the hydrogen evolved so as to avoid explosions. It has also been proposed to introduce the formate into a receptacle previously heated to about 400° C. and maintain the receptacle at that temperature. This method has been found commercially unsatisfactory because of the 55 low percentage of formate resulting therefrom. Other methods of converting formates into oxalates have contemplated the addition of another compound to the formate. This has required separating the 60 foreign element from the oxalate, which is often difficult, and at best an unsatisfactory and expense-involving procedure. Moreover it has long been recognized that the 65 temperature of the formate should be raised 70 suddenly from about 220° C. to 360° C. or over but not exceeding 440° C.; and many efforts have been made to satisfy this condition; but so far as known, the oxalates 75 produced are insufficient in quantity and contain too large a percentage of carbonate.

According to the present invention the formate is converted directly into the oxalate without the addition of any foreign compound, in the presence of air, and by 80 simply and efficiently arranging and controlling the heat zones to which the formate is subjected in order to convert it into the oxalate. The method of the present invention consists in passing the formate through 85 a preliminary heating zone by which it is rendered plastic and then subjecting it to heat not greater than 220° C. by which the formate is rendered molten. At this temperature the formate is stable and there is 90 no liability it will be converted into carbonate. Having slowly raised the temperature of the formate to 220° C. the liquid formate is then suddenly raised to the temperature necessary to drive off the molecule 95 of hydrogen, namely, to a temperature between 360° C. and 440° C. This is done by spreading the liquid formate thinly over hot surfaces of the requisite temperature. By this means the liquid formate is instantly 100 converted into oxalate. When I use the term "instantly" I mean that the operation of converting the formate into oxalate does not take more than two or three seconds. It will be recognized from this that the quantity of 105 carbonate produced is negligible. The great

difficulty heretofore existing in the manufacture of oxalates from formates has been to raise the temperature of the formate from its stable point to the point at which it converts into the oxalate so rapidly that its conversion into carbonate will be prevented. According to the present invention the method employed to raise the formate from its stable point to the point at which it converts into the oxalate is such that although the oxalate is produced quantitatively the formation of carbonate is almost entirely prevented.

The method of the invention may be practiced in various forms of apparatus. A preferred form of apparatus is illustrated in the accompanying drawings, in which Fig. 1 is a front elevation of the apparatus for converting formates into oxalates; Fig. 2 is a side elevation, partly in section, looking from the right in Fig. 1; and Fig. 3 is a vertical transverse section substantially through the middle of the apparatus shown in Fig. 1.

In practicing the method of the invention, the formate is passed in a relatively wide and thin stream through a heated zone by which the temperature of the formate is gradually raised. Passing the formate through this preliminary heating zone renders the formate more or less plastic. The plastic formate is then introduced into a heated receptacle, the temperature of which is sufficient to make the plastic formate liquid. Care is exercised that the temperature of the liquid formate does not exceed 220° C., while it remains in the receptacle, or intermediate heating zone, as it may be termed. By preventing the formate from rising to a greater degree of temperature than 220° C. at this stage of the practice of the method, the formate is insured against being converted into a carbonate. The liquid formate is now spread upon a relatively large heated surface by which its temperature is suddenly raised at 360° C., or slightly over, care being exercised that the temperature of the formate does not exceed 440° C. When the formate has been converted into oxalate on the heated surface, it is scraped off as a fine white powder.

When the steps of the method briefly described above are practiced in the apparatus shown in the accompanying drawings, an oxalate of high percentage is produced. This apparatus comprises means for containing the formate, means for feeding the formate in a wide, relatively thin stream through the preliminary heating zone, means for liquefying the formate, means for spreading the liquefied formate over the heated surface by which it is converted into the oxalate, means for removing the oxalate from the heated surface, and means for conveying the powdered oxalate from the apparatus. The formate in powdered or lump

form is fed into a hopper 5, supported on the upper part of a framework 6 resting on a table 7 supported by the legs or standards 8. The formate is fed into the preliminary heating zone 9 by a feeding device 10 generally indicated by the reference character 10. This feeding device 10 comprises a formate supporting plate 11 which is arcuate in form. The plate 11 is located below the open lower end or bottom 12 of the hopper 5 and supports the supply of formate in the hopper. The formate passes out of the hopper into the preliminary heating zone through a slot or opening 13 formed between the forward end of the plate 11 and the flanged part 14 of the hopper. This slot extends throughout the length of the hopper. It will be recognized from the form and size of the slot 13 that the powdered formate passes down through the preliminary heating zone in a wide relatively-thin stream.

In order to discharge the formate from the hopper, the plate 11 is reciprocated back and forth under the opening 12. In practice it has been found that a reciprocation of forty times a minute and a range of movement of about one-half inch is sufficient to secure a proper feed of the formate. Under certain conditions of operation depending on the nature of the formate treated, the number of reciprocations per minute may be varied and the range of movement may be increased or decreased. The plate 11 is supported for its reciprocatory or oscillatory movements by four arms 15, depending downwardly from hubs 16 secured to a shaft 17 journalled in standards 18 rising from the frame 6. The plate 11 is secured in adjusted position at the lower ends of the arms 15 by check nuts 19. Oscillatory movements are imparted to the shaft 17 by an arm 21 fastened at its upper end to the shaft and having in its lower end a slot 22 which receives a crank 23 or eccentric pin 23 screwed into an eccentric 24 journalled in a standard 25 supported from the table 7. The eccentric pin 23 may be adjusted in the eccentric 24 so as to vary the length of oscillation of the shaft 17 and so the length of reciprocation or oscillation of the plate 11. The eccentric 24 is driven by a sprocket wheel 26 over which passes a chain 27 which is driven by a second sprocket wheel 28 mounted on one end of a hollow shaft 29. The other end of the hollow shaft 29 carries a gear 30 which meshes with a gear 31 carried by a second hollow shaft 32. The other end of the shaft 32 carries a worm gear 33 which is driven by a worm 34 mounted on a shaft 35. The hollow shafts 29 and 32 are mounted in brackets supported from the table 7. The shaft 35 is journalled in brackets mounted on a shelf 36 supported from the table 7.

The shaft 35 carries on its outer end a belt-driven pulley 36 which is connected with a source of power not shown.

The mode of operation of the feeding device 10 will be clearly understood when it is borne in mind that the powdered formate is relatively heavy and has a tendency to move with the plate 11, unless something is in its path of travel to block it. The plate 11 is shown in substantially the neutral position. If it is assumed that the hopper contains the powdered formate and that the plate 11 is moved forward, that is, toward the left, viewing Fig. 3, it will be understood that the formate resting on the plate is carried forward with it and that an open space will be formed adjacent to the bottom of the rear side 39 of the hopper. Into this open space more formate will fall so that as the plate 11 swings rearwardly again, the formate which had been carried forward with the plate is prevented from moving rearwardly with the plate and the formate at the discharge end 40 of the plate 11 will fall down into the chute 20. By reason of the relatively rapid movements of the feed plate 11 it will be recognized that a substantially steady stream of formate drops down into the heating zones.

As the formate passes through the preliminary heating zone 9 in the chute 20 it becomes plastic. The plastic formate drops into a heated trough 42 in which it is immediately liquefied. The trough 42 is provided with a steam jacket 43, which is supplied with steam in any convenient manner. Sufficient heat rises from the trough 42, and also from other sources of heat presently to be described, to keep the preliminary heating zone 9 at the requisite temperature. In fact, the whole apparatus becomes hot after a short period of use and for this reason all the parts are made heavy in order to prevent warping. Only a small quantity of the plastic formate falls into the trough momentarily and it is immediately converted into the liquid state. The heat of the trough is so regulated that the temperature of the liquefied formate does not rise above 220° C.

The liquid formate is at once taken from the trough 42 and spread upon the heated surface by which it is converted into the oxalate. This heated surface consists of a hollow cylinder or drum 45 mounted on the hollow shaft 32. The means for depositing the liquid formate on the heated surface of the drum 45 consists of a rapidly rotating splasher 46 which may be composed of sheet iron or steel mounted on a shaft 47 journaled in brackets supported from the table 7. The shaft 47 is provided with a pulley 48 over which passes a belt 49 driven by a pulley 50 on the end of the shaft 51 of a motor 52. The splasher 46 acts as a scoop to gather up the liquid formate in the bot-

tom of the trough 42 and throw it by centrifugal force upon the revolving surface of the hot drum 45. At each revolution of the shaft 47 the splasher 46 cleans out the trough 42 so that no formate may remain therein to be slowly converted into carbonate.

Only a thin layer of the liquid formate is spread over the heated surface of the drum 45 by the action of the splasher 46. The drum 45 is maintained at such heat that the formate upon it is almost or substantially instantaneously converted into oxalate, not more than two or at most three seconds being required to effect the conversion. In case the liquid formate should be spread upon the drum 45 too thickly to be instantly converted into oxalate, a second drum 54 is provided, the surface of which travels in close proximity to the surface of the drum 45, as clearly shown in Fig. 3. If the formate on the surface of the drum 45 is so thick that it touches the surface of the drum 54 as it passes through the opening 55 between the two drums, the top surface of the material on the drum 45 will adhere to the hot surface of the drum 54 where it is instantly converted into oxalate. The drum 54 is mounted on the hollow shaft 29.

The drums 45 and 54 are provided internally with gas burners 56, the mixture of gas and air being supplied through the hollow shafts 29 and 32. It will be understood that the heating may be done by electricity, oil, powdered coal or otherwise. In order that the heat may be distributed uniformly over the surfaces of the drums 45 and 54, a layer of some granular, refractory material 57 such as flint or quartz sand is provided at the bottom of each drum. This granular material, of course, tends to remain in the bottoms of the drums as they revolve, thereby conveying the heat to the cylindrical surfaces of the drums uniformly, an action which cannot be successfully accomplished by direct heating. Radiation pyrometers may be used for registering and thermostats for controlling the outside temperature of the drums. The products of combustion may be conveyed from the apparatus through the pipe 58. The draught of the burner in the drum 54 is controlled by the damper 60, and the draught of the burner in the drum 45 is controlled by the damper 59.

The drums turn in the directions indicated by the arrows in Fig. 3. The oxalate is removed from the drum 45 by a knife-like scraper 62 supported on the upper ends of plungers 64 pivotally connected at 65 to levers 66 pivoted to the frame of the apparatus at 67. The free ends of the levers 66 rest on springs 68 surrounding the upper ends of upright rods 69. The springs 68 serve to press the scraper 62 against the surface of the drum 45 in order to keep it

clean. The pressure of the springs 68 may be regulated by turning the screws 70. The oxalate is removed from the surface of the upper drum 54 by a knife-like scraper 72 secured in the lower end of plungers 73 working in a beam 74 arranged transversely at the top of the apparatus. Pressure is exerted upon the scraper 72 by springs 75 surrounding rods 76 the upper ends of which 10 are received in brackets 77. The pressure of the springs 75 may be regulated by turning the rods 76 which are provided with squared ends 78 for that purpose. The scrapers are composed of some high speed 15 tool steel and are arranged so that the edges are kept in good scraping condition.

The oxalate removed from the surfaces of the drums and which is now in powdered form falls into a trough 80 in the lower end 20 of which there is a screw conveyer 81 fixed on a shaft 82 journaled in the frame of the apparatus. One end of the shaft 82 is provided with a screw gear 83 which meshes with a screw 84 mounted on one end of the 25 shaft 35. The screw conveyer 81 conveys the powdered oxalate into a receptacle 85 provided with a removable part 86. The guard 87 is provided to prevent the oxalate scraped from the upper drum 54 from falling 30 onto the floor.

It will be recognized from the description of the apparatus illustrated in the drawings that this apparatus constitutes an effective means for carrying out the method of the 35 invention. Only small quantities of the formate are subjected to the various heated zones at one time and the heat of these zones is so regulated that there is no opportunity for the formate to convert into 40 carbonate. Inasmuch, however, as the operation is one of great rapidity, there is a continuous stream of formate passing into the apparatus and a continuous stream of oxalate passing out of the apparatus.

45 Having thus described the invention, what is claimed is:

1. The method of converting formate into oxalate which comprises passing the formate through a preliminary heating zone by 50 which the formate is rendered plastic, introducing the plastic formate into a heated receptacle by which the formate is liquefied, preventing the formate from rising above

220° C. while in the receptacle, removing the liquid formate from the receptacle, 55 spreading it in a thin layer over a relatively large surface having a temperature between 360° C. and 440° C. by which it is converted into oxalate, and removing the oxalate from the heated surface. 60

2. The method of converting formate into oxalate which comprises slowly liquefying the formate and raising its temperature to 220° C., then spreading the liquefied formate in a thin layer over a heated surface by 65 which the temperature of the formate is suddenly raised to a point between 360° C. and 440° C. whereby the formate is converted into oxalate, and then removing the oxalate from the heated surface. 70

3. The method of converting formate into oxalate which comprises liquefying the formate at a temperature not higher than 220° C. and then suddenly raising the temperature of the formate to a point between 75 360° C. and 440° C. whereby the formate is converted into oxalate.

4. The method of converting formate into oxalate which comprises feeding the formate through a heated zone to render it plastic, 80 raising the temperature of the formate to a point not higher than 220° C. to liquefy it, spreading the liquid formate out in thin layers and suddenly raising its temperature to a point between 360° C. and 440° C. 85 whereby it is converted into oxalate.

5. The method of converting formate into oxalate which comprises subjecting the formate to heat to render it plastic, raising the temperature of the plastic formate not 90 higher than 220° C. to liquefy it, and then suddenly raising the temperature of the liquid formate to a point between 360° C. and 440° C. whereby it is converted into oxalate. 95

6. The method of converting formate into oxalate which comprises bringing the formate in contact with a surface maintained at a temperature not greater than 220° C. whereby the formate is liquefied, 100 and then bringing the liquefied formate in contact with a surface maintained at a temperature between 360° C. and 440° C. whereby the formate is converted into oxalate.

HERMAN W. PAULUS.
